Primary Examiner—Robert M. Spear*Assistant Examiner*—Susan E Krakower*(74) Attorney, Agent, or Firm*—Ladas and Parry LLP(57) **CLAIM**

I claim the ornamental design for a pacifier, as shown and described.

DESCRIPTION

FIG. 1 is a top plan view of a pacifier showing my new design;

FIG. 2. is a front elevational view thereof;

FIG. 3 is a left side elevational view, the right elevational view being a mirror image thereof;

FIG. 4 is a back elevational view thereof.

FIG. 5. is a bottom plan view thereof; and,

FIG. 6 is a perspective view thereof.

The broken line showing of a shield illustrates unclaimed environmental structure.

Protection is sought for the shape and ornamental features of the suction part. The shank of the suction part is not hollow but single-walled and thus rather thin, in addition slightly bended. The actual suction part has, seen from the front, a more ring-shape, and, seen from the side, it is curved (convex) on the upper side and flattened on the bottom side, with openings at the sides.
